UNITED STATES PATENT OFFICE.

LEWIS B. NIEMANN, OF STAPLEHURST, NEBRASKA.

TELEPHONE SYSTEM.

No. 857,480.

Specification of Letters Patent.

Patented June 18, 1907.

Application filed March 8, 1907. Serial No. 361,336.

To all whom it may concern:

Be it known that I, LEWIS B. NIEMANN, a citizen of the United States, residing at Staplehurst, in the county of Seward and State of Nebraska, have invented new and useful Improvements in Telephone Systems, of which the following is a specification.

This invention relates to telephone systems of the metallic return type in which 10 grounded ringing magnetos are employed at the subscribers' stations and grounded signal drops at the telephone office or exchange for signaling the exchange operator when a subscriber desires a connection with another 15 subscriber in the system, and it relates more particularly to the employment of an auxiliary drop at the exchange station, whereby a subscriber after completing a conversation with a certain subscriber can quickly and 20 positively signal the operator for connection with another subscriber, and this even should the cord circuit of the operator remain plugged in and the signal drop cut out.

In the usual telephone systems having 25 grounded ringing generators and signal drops, the clearing drop often fails to operate, with the result that the operator leaves the cord circuit plugs in the jacks after two 30 subscribers have ceased talking. As long as the plugs remain in neither one of the subscribers can call the operator by the usual signal drops, thus causing a long and tedious delay, until the operator of her own choice tests to see if the line is still busy, and if not, 35 takes out the plugs, whereupon the circuits are restored to normal condition and the waiting subscriber can then signal the operator and get the desired connection.

The principal object of the present invention is to overcome the objections above noted by providing a supplemental drop which is wound to have a low resistance so that a current of comparatively low value will insure the operation of the drop, thereby 45 enabling the subscriber to quickly signal the operator by means of the magneto and thus obviating the usual waiting that subscribers experience in the common form of party or rural line telephone systems.

With these objects in view and others, as will appear as the description proceeds, the invention comprises the various novel features of construction and arrangement of parts which will be more fully described here-

inafter and set forth with particularity in the 55 claims appended hereto.

In the accompanying drawing, which illustrates one of the embodiments of the invention, the figure shows diagrammatically the supplemental drop circuit in connection 60 with the usual telephone circuit with which it is intended to be employed.

In the present instance, the calling circuits at the switch-board, as well as the speaking and receiving apparatus of the subscriber's 65 telephone set have been dispensed with since the same are not essential to an understanding of the present invention.

Referring to the drawing, A and B designate respectively the usual calling and clear-out-out drops of a telephone system that are connected by a metallic return circuit with a ringing magneto C at the subscribers' stations, one of such magnetos being shown in the present instance. In the line 1 of the 70 circuit between the subscriber's station and the switch-board at which the drops are located, is a push button switch designated generally by 2 that is located at the subscriber's station so as to connect the magneto either to 75 ground or to the metallic or line circuit. This switch comprises a spring 3 that normally makes contact with a contact 4, and when actuated, is adapted to engage the contact 5 that is connected to ground by the conductor 6. The spring 3 is permanently connected by the conductor 7 with the magneto 3. The other line 8 of the metallic circuit is connected with the magneto and with the contact or spring 9 on the answer jack 10. 80 This spring is connected with the coil 11 of the signal drop A and thence to ground by the conductor 12. The side 1 of the line circuit is connected with the spring 13 of the jack and when the plug 14 is placed in the 85 jack 10, the metallic circuit is completed through the conductors 15 and 16 of the usual cord circuit and the drop A is cut out of service. Bridged across the cord circuit by the switch 17 is the clearing-out drop B connected with the switch by conductors 18 and 19. 90

The system of circuits thus far described is well known and in connection therewith the supplemental signaling device constituting the present invention is employed. This 105 signaling device comprises a supplemental drop D which is of the usual construction and is preferably wound so as to be of very

low resistance. One end of the coil 20 of the drop D is connected to the line 18 by the conductor 21, while the other end is connected by the conductor 22 to ground. When the 5 coil is energized, the armature 23 is attracted and the lever 24 raised so as to permit the shutter 25 to fall to signal the operator.

In operation, when a subscriber desires to 10 signal to the exchange operator, the armature of the generator C is rotated in the usual manner, while the push button switch is actuated to connect one side of the circuit to ground. The current passes through the conductor 8, through the coil 11 to ground 15 by way of the conductor 12 and back to the generator through the conductor 6, switch-spring 3 and conductor 7. The current passing through the coil 11 attracts the armature of the signal drop A so that the shutter there- 20 is opened to attract the attention of the operator. The answer plug is then inserted in the jack 10, thereby cutting out the drop A and enabling operator by means of her telephone set to ascertain the number of the 25 subscriber desired. After thus ascertaining the number, operator places the call plug in the jack of the subscriber wanted and the two subscribers are then connected for conversation. After the conversation is fin- 30 ished, the subscribers turn their magnetos so as to supply current for energizing the clearing-out drop B. Under some conditions, the current is not sufficient to energize the clearing-out drop, as for instance, when a number 35 of receivers in the telephone system are down or when the resistance caused by the telephones in circuit is too great. In case one of the subscribers should wish to call the operator immediately after closing conversation 40 with the other subscriber and the clearing-out drop should not operate, it is difficult to attract the exchange operator's attention. Long waits are often caused, and furthermore, the subscriber more often attempts to 45 signal the operator by actuating the magneto while holding the switch 2 pressed, thereby connecting the magneto to ground. While the circuit is in this condition, it is obvious that the operator cannot be signaled accord- 50 ing to the former method employed in magneto systems. With the present supplementary drop D, the subscriber can positively signal to the operator for the reason that a current of very low strength will actuate the said drop. When the subscriber operates the magneto and at the same time 55 presses the switch 2, the circuit is completed through the path formed by the conductor 8, jack switch 9, tip of the plug 14, and con- 60 ductor 15, switch 17, conductors 18 and 21, coil 20 and conductor 22 to ground and thence back to the magneto through the grounded conductor 6, switch spring 3 and

conductor 7. It will thus be seen that should the usual clearing-out drop fail to operate as to inform the operator that the conversation is completed and that the plug should be taken out to enable the drop A to signal in the usual manner, the supplementary drop will operate to inform the operator 65 that the subscriber previously talking wishes another connection. By connecting the supplementary drop in a grounded circuit, it is obvious that this drop will not operate by a current passing only through the metallic 70 circuit of the system. Thus, when the clearing-out drop is operated in the usual manner, the supplementary drop remains closed and only operates under the emergency conditions above set forth. 75

From the foregoing description taken in connection with the accompanying drawing, the advantages of the construction and of the method of operation will be readily apparent to those skilled in the art to which the invention appertains, and while I have described the principle of operation of the invention, together with the apparatus which I now consider to be the best embodiment thereof, I desire to have it understood that the apparatus shown is merely illustrative and that such changes may be made when desired, as are within the scope of the claims. 80

Having thus described the invention, what I claim is:—

1. In a telephone system, the combination of a subscriber's station including a source of ringing current, and means for establishing a grounded circuit; with an exchange station including a grounded signal drop, and a 95 clearing-out drop; a circuit connecting the subscriber and exchange stations together; and a supplemental signal at the exchange station connected in circuit to be operated by a current derived from a subscriber's station. 100

2. In a telephone system, the combination of a subscriber's station including a generator, and means for grounding the same; a central station including a grounded signal drop, a clearing-out drop, and a metallic circuit connecting the said drops with the subscriber's station; and a supplementary signal connected with one side of the metallic circuit and connected with ground to be energized by current from the generator when the latter is grounded. 110

3. In a telephone system, the combination of a subscriber's station including a magneto, a metallic circuit connected therewith, a grounded conductor, and a switch for opening the metallic circuit and connecting the grounded conductor with the magneto; with a central exchange including a grounded signal drop, a jack connected with the metallic circuit, a cord circuit having a plug for connecting the latter with the metallic circuit 120

leading to the subscriber's station and for cutting out the signal drop; and a clearing-out drop included in the cord circuit; and a supplemental signal drop of low resistance connected with one side of the circuit including the clearing-out drop and also connected with the ground.

In testimony whereof, I affix my signature in presence of two witnesses.

LEWIS B. NIEMANN.
